UNITED STATES PATENT OFFICE.

FRANK W. SHUPERT, OF SANFORD, FLORIDA.

STAY-BOLT CONSTRUCTION.

Application filed June 9, 1924. Serial No. 718,871.

The present invention relates to improvements in boiler staybolt constructions, and more specifically to an improved flexible staybolt construction for affording some elasticity between the inner and outer firebox sheets of the boiler, whose different rates or degrees of expansion cause numerous breakages of the staybolts now in common use.

10 The primary object of the invention is to provide a flexible staybolt construction, designed to permit of slight relative movement, due to expansion and contraction, of the two plates which it connects, in a manner 15 to prevent bending or shearing of the bolt.

A further object of the invention is to provide an improved mounting for the headed end of a staybolt, having a bearing member so associated with the headed end 20 of the staybolt and with the outer surface of the wrapper or outer firebox sheet as to permit of lateral movement of the bearing member with respect to the wrapper sheet as well as movement of the shank and head of 25 the staybolt with respect to the bearing member.

A still further object of the invention is to provide improved staybolt constructions embodying sealing caps for preventing leakage, and having the sealing caps so formed 30 as to permit of the inspection of the staybolts without the necessity of removing the sealing caps from the wrapper sheet.

Other objects and advantages of the invention will appear in the following detailed description, taken in connection with the accompanying drawing, forming a part 35 of this specification, and in which drawing;

40 Figure 1 is a fragmentary section through the fire-box portion of a boiler and showing a staybolt construction embodying my invention;

Figure 2 is a section on the line 2—2 of 45 Figure 1 and looking in the direction of the arrows; and,

Figure 3 is a fragmentary section through the crown of the sealing cap, and illustrating the manner of repairing the cap after 50 the required inspection of the stay bolt.

Referring to the drawing in detail, and wherein similar reference characters designate corresponding parts throughout the several views; A designates a fire-box portion of a boiler embodying a wrapper or outer fire-box sheet B and an inner fire-box

sheet C; D a button head type of staybolt; E a slidable mounting for the headed end of the staybolt, and F a cover means for enclosing the slidable mounting E and the 60 head of the staybolt D.

The wrapper sheet B is provided with an opening 5 which is normally disposed in axial alignment with a screw threaded opening 6 provided in the inner sheet C. The 65 opening 5 is substantially larger than the shank 7 of the staybolt D thus permitting lateral movement of the shank within the opening 5; while the screw threaded opening 6 is of a size for screw threaded engagement with the threaded end portion of the 70 staybolt. The inner end of the staybolt may be secured to the inner sheet C in any suitable manner.

The staybolt D, which may be of the button 75 head type, has the head portion 8 thereof, which is of greater diameter than the opening 5, formed with an annular convexed inner face 9. The head 8 may be provided with a wrench receiving recess 10 to facilitate screwing the staybolt into the inner 80 fire-box sheet C.

Referring to the slidable mounting E, the same preferably consists of a loose washer 11, provided at one side with a concaved annular seat 12, acting as a seat for the convex portion of the head 8, and having its other side formed flat for surface engagement with the outer face of the wrapper sheet B. The bore of the washer 11 is also 85 of greater diameter than that of the shank 7 of the staybolt.

It will be seen from the dotted line shown 90 in Figure 1, that relative movement of the sheets B and C, due to expansion and contraction of the two sheets, will cause the mounting E to slide on the wrapper sheet in a plane parallel to the face of the sheet, and the staybolt to move bodily instead of 95 merely pivotally, this preventing bending or possible shearing stresses at its inner end which is rigidly secured to the inner sheet C. The concave seat formed in the mounting E also permits of a slight movement of the head 8 within the mounting.

The cover means F for enclosing the mounting E and the head of the staybolt D, consists of a hollow semispherical shell 13 having an inspection cap 14 integral with 100 and projecting outwardly from the crown thereof. This shell, which is of a size to permit of sliding movement of the washer

11 in any direction, is welded as at 15 to the outer face of the wrapper sheet B to provide a steam tight cover.

When inspection in accordance with the Federal, State, or municipal requirements, are to be made, the cap 14 may be burned off, with a torch for permitting of the inspection of the staybolts without the necessity of removing the entire cover from the wrapper sheet. If the staybolt is found to be in proper condition, the opening in the cover may be welded over, or a new cap welded to the shell as shown at 16 in Figure 3 of the drawing, thereby sealing the cover. It is of course to be understood that should the staybolt be found to be broken, then the whole cover will necessarily need to be disconnected from the wrapper sheet.

It will therefore be seen that a novel flexible staybolt construction has been provided whereby all bending or shearing stresses at the inner connection of the staybolt will be eliminated, and incorporating a novel cover means whereby inspection of the bolts may be readily accomplished in an efficient manner.

Changes in detail may be made without

departing from the spirit of the invention or the scope of the following claims; but,

I claim:

1. In combination with spaced inner and outer fire-box sheets, a staybolt construction comprising a bolt including a shank, a screw threaded portion at one end of the shank, fixed in screw threaded engagement to the inner fire-box sheet, and a relatively shallow button-like head integral with the opposite end of the shank and disposed exteriorly of the outer fire-box sheet with the shank freely movable laterally in an opening of said last mentioned sheet and the face of the head confronting the outer sheet being convex in shape; and a mounting for the headed end of said bolt comprising a ring like member slidable over the face of the outer sheet and having a concaved annular seat for the convex faces of said head.

2. A staybolt cover comprising a one piece hollow semi-spherical shell welded about the staybolt opening in the fire box sheet, and a relatively small hollow inspection cap formed integral with and projecting from the crown of said shell.

FRANK W. SHUPERT.
